DISPLAY BOX

David Levkoff, Brooklyn, N. Y.

Application July 11, 1938, Serial No. 218,492

4 Claims. (Cl. 206—44)

This invention relates to improvements in cardboard boxes and more particularly to display boxes having a hinged cover.

One of the main objects of the invention resides in a cardboard box of the type in which the front wall of the box body is cut away to display the contents of the box from the front when the hinged cover is in open position, wherein the said front wall cooperates with the cover to secure the latter in closed position and further serves to provide support for the cover to prevent sagging or inwardly crushing of the cover under pressure from above, such as when a number of boxes are piled one upon the other.

Another feature of the invention is to provide a box in which the cut-away front wall is reinforced by forming the same of a double thickness to support the front end of the hinged cover under any ordinary pressure or load to which the cover may be subjected.

A further feature of the invention is the provision of cardboard box in which the front flap of the hinged cover may be guided into its proper interfitting position with respect to the front wall of the box body to facilitate and expedite the swinging of the cover to fully closed position.

A still further feature of the invention is to provide a cardboard display box having the above mentioned improvements which does not increase the cost of the box over previous cardboard boxes of this general type.

Other features of the invention will appear as the following specification is read in conjunction with the accompanying drawings, in which:

Figure 1 is a perspective view of my improved box with the cover in partially open position.

Figure 2 is a front elevational view with the cover fully closed and with parts broken away in section.

Figure 3 is an enlarged vertical sectional view on the line 3—3 of Figure 2.

Figure 4 is an enlarged vertical sectional view on the line 4—4 of Figure 2.

Figure 5 is a horizontal sectional view on the line 5—5 of Figure 4.

Figure 6 is a front elevational view of a slightly modified form of the invention with parts broken away in section.

Figure 7 is an enlarged vertical sectional view on the line 7—7 of Figure 6.

Figure 8 is a perspective view of a further modified form of box illustrating the cover in a partially open position.

Figure 9 is a front elevational view of the box

shown in Figure 8 with the cover in closed position.

Figure 10 is an enlarged vertical sectional view on the line 10—10 of Figure 9.

Like reference characters refer to like parts throughout the several forms of the invention herein described.

Referring to the drawings by reference characters, the numeral 10 designates the preferred form of my cardboard box in its entirety and which is of rectangular shape in configuration, although the invention about to be described may be embodied in boxes of other shapes if desired. The box 10 includes a body 11 comprising a bottom wall 12, parallel upstanding side walls 13—13, a rear end wall 14, an inner relatively low front end wall 15 consisting of overlapping flaps 15a—15a which are respectively formed integral with the side walls 13—13, and an outer front end wall 16 formed integral with the bottom wall 12. Formed integral with and extending inwardly from the top of the side walls 13—13 are flaps 17—17. A cover 18 is hinged to the top of the rear end wall 14 as at 19 and has a hinged downwardly extending front flap 20 at the front end thereof.

The box 10 including the body 11 and hinged cover 18 may be constructed from a single blank of cardboard folded into the set up position as illustrated in the drawings, or the box may be made of two or more foldable blanks pasted, stitched, or otherwise secured together. The essential features of the invention will be more fully explained hereinafter.

The inner front end wall 15 is cut inwardly from the top as at 21 so that each flap 15a is provided with an upwardly extending front corner extension 22, the inner side edges of the flap extensions 22 converging downwardly so that the opening in the front of the body is wider at the top than at its bottom.

Formed integral with the outer front wall 16 is a lock flap 23 hinged on the fold 24, the same being of a height equal to the height of the front wall flaps 15a and which lock flap has spaced tongues 25—25. The lock flap 23 is of a width equal to the width of the bottom of the opening in the front and is folded inwardly through the opening and flat against the inner sides of the flaps 15a of the inner front wall 15 as best illustrated in Figure 5 of the drawings. The tongues 25—25 enter slots 26—26 in the bottom wall 12 at the front end thereof to secure the folded lock flap 23 against accidental unfolding. The lock flap 23 when in locked position acts to pre-

vent outward separation of the lapping front flaps 15^a and thus holds the front end of the body 11 in rigid set up position.

The cover locking flap 20 is provided with a tongue extension 27 which is of a width equal to the width of the fold 24 of the flap 23 and disposed on opposite sides of the tongue extension 27 are relatively short semi-circular shaped tongues 28-28. Notches 29-29 are formed between the inner edges of the tongues 28 and the side edges of the tongue extension 27. When the hinged cover 18 is swung to closed position over the body 11, the tongue extension is inserted inwardly of the front end of the body to lie against the flap 23, while the short tongues 28-28 respectively engage the outer sides of the flap extensions 22-22 and as they slide downwardly thereagainst they are guided to a position into pockets 29 formed between the extensions 22 and the outer ends of the outer front wall 16. When the cover reaches the limit of its closing movement, the ends of the fold 24 enter the notches 29, thus limiting the closing movement of the cover and providing a support for the front end of the cover although the tongue 27 terminates short of the bottom 12 of the box body 11. The extensions 22-22 also act as stops for preventing the inward swinging of the front cover flap 20. The tongue extension 20 serves to close the open portion of the cut-away or notched front wall 15.

Heretofore in display boxes of this type, the cover relied upon the side top flaps 17 and the engagement of the cover flap with the bottom wall of the box body for the support of the cover against any pressure applied thereto when the cover is in closed position. Such construction is insufficient to withstand the pressures to which boxes are subjected when stacked for shipment, resulting in the inward crushing of the cover and disfigurement of the display box as a whole. Whereas in my construction the side flaps 17 act as a seat for supporting the intermediate portion of the cover 18, the interfitting of the notches 29 with the ends of the low front wall of the box, act to firmly support the cover against accidental inward crushing.

In the form of the invention shown in Figures 1 to 5, the cover 18 when closed is free to be swung to open position, but in Figures 6 and 7 I have shown a slight modification wherein the cover may be locked in closed position. The construction shown in Figures 6 and 7 is the same as that previously described, with the exception that the tongues designated 28'-28' are wider than the tongues 28-28 heretofore described and are notched inwardly to provide hook portions 30 which may be forced past the ends of the fold 24 to engage beneath the fold and become locked thereto. To open the cover it is only necessary to flex the tongues 28' outwardly to disengage the hook portions from the ends of the fold 24.

In Figures 8 to 10 inclusive I have illustrated a further modified form of my invention wherein the lapping flaps 15^a-15^a, outer front end wall 16, and an inwardly folded flap 23' are held together by a metal stitch or staple 31. The flap 23' is similar to the flap 23 heretofore described but it terminates short of the bottom wall of the box body for in this form the stitch 31 is relied upon to hold the front end of the box in assembled position instead of the interlocking of the infolded flap with the bottom wall. Also, in this form of the invention the

tongues 28 on the cover flap are dispensed with and the corners 32 between the tongue extension 27 and front cover flap 20 act as the equivalent to the notches 29 and engage the ends of the top edge of the low front wall structure of the box body. Whereas the support for the front end of the cover shown in this modified form is substantially the same as that in the preceding forms, this construction is more difficult for an operator to handle when moving the cover 18 to closed position for the guide tongues 28 are absent, and which tongues 28 facilitate the guiding of the longer tongue 27 inwardly of the low front wall of the box.

In display boxes of the kind herein set forth, it is customary to provide the cover 18 with a transverse score line 33 whereby the cover when open may be folded upon itself and the front cover flap inserted down against the inner side of the rear end wall 14 and the folded cover held by the rear ends of the side flaps 17-17 whereby the folded cover will stand upright and display any advertising indicia which may be printed thereon. Thus the box 10 may be opened and placed upon a counter or in a store window to clearly display the contents of the box and any advertising indicia printed upon the cover.

While I have shown and described several embodiments of my invention, I wish it to be understood, that such further modifications as come within the spirit of the invention may be resorted to if desired.

Having thus described the invention, what I claim as new is:

1. A cardboard display box comprising a body having a bottom wall, opposed side walls, a rear wall, an inner front wall composed of two freely lapping front flaps formed integral with the side walls and being of a height less than said side walls, corner extensions rising upwardly from said flaps, an outer front wall formed integral with the bottom wall and lying flat against said inner front wall, a flap formed integral with said outer front wall and folded rearwardly over the inner front wall to lie flat thereagainst, means securing said outer front wall, inner front wall, and said last named flap together, flaps integral with the top of the side walls and folded inwardly therefrom, a cover hinged to said rear wall and overlapping the last named flaps when in closed position, a front cover flap hinged to the front end of said cover, and a reduced tongue extension formed integral with said cover flap, the combined width of said front cover flap and tongue extension being less than the depth of said body, said tongue extension fitting inside of said body and terminating short of the bottom wall thereof while the ends of said cover flap rest upon the fold between the outer front wall and the inwardly folded flap formed integral therewith to support the front end of said cover free of said bottom wall.

2. A cardboard display box comprising a body having a bottom wall, opposed side walls, a rear wall, an inner front wall composed of two lapping front flaps formed integral with the side walls and being of a height less than said side walls, corner extensions rising upwardly from said flaps, an outer front wall formed integral with the bottom wall and lying flat against said inner front wall, a flap formed integral with said outer front wall and folded rearwardly over the inner front wall to lie flat thereagainst, means securing said outer front wall, inner front wall, and said last named flap together, a cover hinged to said rear

wall, a front cover flap hinged to the front end of said cover, and a reduced tongue extension formed integral with said cover flap, said tongue extension fitting inside of said body and closing the open front portion thereof while the ends of said cover flap rest upon the fold between the outer front wall and the inwardly folded flap formed integral therewith to support the front end of said cover, and tongues formed integral with the front cover flap at opposite sides of said tongue extension adapted to engage with said corner extensions when the cover is being swung to closed position and fitting between said corner extensions and adjacent portions of said outer front wall when the cover is in fully closed position.

3. A cardboard display box comprising a body having a bottom wall, opposed side walls, a rear wall, an inner front wall composed of two lapping front flaps formed integral with the side walls and being of a height less than said side walls, corner extensions rising upwardly from said flaps, an outer front wall formed integral with the bottom wall and lying flat against said inner front wall, a flap formed integral with said outer front wall and folded rearwardly over the inner front wall to lie flat thereagainst, means securing said outer front wall, inner front wall, and said last named flap together, a cover hinged to said rear wall, a front cover flap hinged to the front end of said cover and a reduced tongue extension formed integral with said cover flap, said tongue extension fitting inside of said body and closing the open front portion thereof while the ends of said cover flap rest upon the fold between the outer front wall and the inwardly folded flap formed integral therewith to support the front end of said cover, and tongues formed integral with the front cover flap at opposite sides of said

tongue extension adapted to engage with said corner extensions when the cover is being swung to closed position and fitting between said corner extensions and adjacent portions of said outer front wall when the cover is in fully closed position, and hook portions formed on said tongues for hooking engagement beneath and at the ends of the fold between said outer front wall and inwardly folded flap to secure said cover in locked position with said body.

4. A cardboard display box comprising a body having a bottom wall, opposed side walls, a rear wall, an inner front wall composed of two lapping front flaps formed integral with the side walls and being of a height less than said side walls, corner extensions rising upwardly from said flaps, an outer front wall formed integral with the bottom wall and lying flat against said inner front wall, a reduced flap formed integral with said outer front wall and folded rearwardly over the inner front wall to lie flat thereagainst, a metal staple passing through said outer front wall, said front flaps, and said infolded flap to secure the same together, a cover hinged to said rear wall, a front cover flap hinged to the front end of said cover, and a reduced tongue extension formed integral with said front cover flap, the combined width of said cover flap and said tongue extension being less than the depth of said body, said tongue extension fitting into said body and terminating short of the bottom wall thereof while the ends of said cover flap beyond the opposite sides of said tongue extension seat upon the fold between the outer front wall and the inwardly folded flap formed integral therewith to support the front end of said cover when the same is in closed position.

DAVID LEVKOFF.
